UNITED STATES PATENT OFFICE.

HOMER WORDEN, OF NEW YORK, N. Y.

DESIGN FOR A BOTTLE-CASE.

SPECIFICATION forming part of Design No. 35,167, dated October 8, 1901.

Application filed August 24, 1901. Serial No. 73,208. Term of patent 7 years.

To all whom it may concern:

Be it known that I, HOMER WORDEN, a citizen of the United States, residing in the city, county, and State of New York, have invented and produced a certain new and original Design for a Bottle-Case, of which the following is a specification.

This is a design for a bottle-case, and relates to the shape thereof.

10 The new design is shown in the accompanying drawing, in which the figure is a perspective view of a bottle-case embodying the new design.

Referring to the drawing, the design as a whole may be considered as composed of three parts A, B, and C, the part B being intermediate between the upper and lower end portions A and C. The part A has a smooth convex and substantially conical surface *a*, 15 which terminates at its lower end in a spiral band or convolution *b*, which is finished off by a slightly-extending flange *c*. The part B is similar in design to the part A, but of smaller size, having an upper smooth convex 20 and substantially conical surface *d*, termin-

nating at its lower edge in a spiral convolution *e*, at the lower edge of which it joins the upper small end of the part A. The part C is very slightly conical, as shown at *f*, and is smooth throughout the greater portion thereof, being bordered at its upper end by an extending outwardly-curved rib *g* and being substantially flat on top, as shown at *h*.

The case embodying the new design has a distinctive and pleasing appearance, the successive bands and smooth convex surfaces and the upper cylindrical cap-shaped portion being distinctive features of my present design.

What I claim is—

25 The design for a bottle-case substantially as herein described and shown.

In witness whereof I have hereunto signed my name in the presence of two subscribing witnesses.

HOMER WORDEN.
